By Daniel W. Parker, Atty.

UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 28,009, dated December 7, 1897.

Application filed October 23, 1897. Serial No. 656,234. Term of patent 14 years.

To all whom it may concern:

Be it known that I, FRANK L. WRIGHT, a citizen of the United States, residing at Chicago, in the county of Cook and State of Illinois, have invented a certain new and original 5 Design for Prism-Plates, of which the following is a description.

My invention relates to designs for prism-plates.

10 Figure 1 is a plan view of a prism-plate embodying my design. Fig. 2 is a cross-section therethrough on line 2 2.

A is the body of the prism-plate; B B, a series of surface areas substantially uniform 15 produced by the lines of separation C C.

D D are prisms on one side of the prism-plate, and E E prisms on the other side of the prism-plate and produced upon a series of the

surface areas about or near the edge of the prism-plate, so as to form a sort of border. 20

The essential features of my design are found in a prism-plate comprising a substantially flat extended body with prisms on one side, lines of separation on the other side, which divide the surfaces into a series of substantially uniform surface areas, and prisms on such surface areas about or near the edge, so as to form a sort of border. 25

I claim—

20 A design for a prism-plate, substantially as shown and described.

FRANK L. WRIGHT.
